(57) CLAIM

The ornamental design for a note dispenser, as shown and described.

DESCRIPTION

FIG. 1 is a perspective view showing the new design for a note dispenser;

FIG. 2 is a top view thereof;

FIG. 3 is a front view thereof;

FIG. 4 is a bottom view thereof;

FIG. 5 is a back view thereof; and,

FIG. 6 is a side view thereof, the opposite side being a mirror image.

The broken lines in FIGS. 1-6 are included for the purpose of showing portions of the note dispenser that form no part of the claimed design.
